UNITED STATES PATENT OFFICE.

ALLEN E. SHIPPEE, OF EAST PROVIDENCE, RHODE ISLAND, ASSIGNOR TO STONE & WEBSTER, INC. OF BOSTON, MASSACHUSETTS, A CORPORATION OF MASSACHUSETTS.

METHOD OF MAKING CARBURETED WATER GAS.

Application filed January 18, 1921. Serial No. 438,115.

This invention relates to the manufacture of carbureted water gas and has for its object a process of making gas in the usual gas making set, comprising a generator, carburetor and superheater, whereby oil having a relatively high sulphur and coke making content may be employed and the amount of carbon disulphide in the carbureted gas kept down to a low and commercially unobjectionable value.

Attempts have been made, heretofore, to use oils having a high sulphur and coke making content, of which Californian and Mexican crudes are typical examples, by spraying the oil in the carburetor in the usual manner. The resulting gas product, however, has such a high carbon disulphide content as to be extremely objectionable. Hydrogen sulphide is also formed but may be easily removed from the gas.

When oil having a high coke making content is sprayed into the carburetor, coke will be deposited on the bricks composing the checker work of the carburetor. The coke may first form upon the bricks of the first two or three courses and may then be built up gradually on lower courses. The building up of the coke deposit gradually reduces the area of the gas passages through the carburetor. The coke deposit is formed at a relatively slow rate, however, and it is found that the gas making process may be carried on for a period of from twelve to twenty-four hours without a serious reduction of gas passage area in the carburetor even when an oil of high coke depositing content is used. This accumulation of coke in the carburetor has not hitherto been recognized as important in connection with the formation of an excess of carbon disulphide in water gas. When oil is used having a high sulphur content and which forms a large amount of free carbon, it is natural to assume that the resultant gas would be likely to contain a large amount of carbon disulphide. I have found, however, that by removing the coke deposited on the carburetor checkerwork at frequent intervals, for instance, between each gas making run, there will be no serious formation of carbon disulphide, notwithstanding the fact that the oil may be very high in sulphur and coke-producing con-

tents. Even when the carbon is burned off between each gas making run there is, nevertheless, deposited on the checkerwork during each run a measurable amount of carbon, more than enough to cause harmful results if converted into carbon disulphide, but I have found that the carbon disulphide is not in fact produced in harmful quantities if the carbon is burned off at frequent intervals, as between each gas making run, even when an oil depositing a large amount of coke is used.

By the use of my process without changing the ordinary apparatus used for making water gas, I can burn out the coke deposited in the carburetor by oils of very large sulphur and coke making content at frequent intervals thus keeping the carburetor at all times free of coke sufficient to react harmfully and by so doing, the formation of carbon disulphide to a prohibitive extent, is prevented. This can be done with little or no loss of efficiency in the apparatus.

In carrying out my invention, I burn out the coke in the carburetor preferably between each run or gas making period so that the carburetor is free, or substantially free, of coke on each run. The burning operation is carried out by forcing air through the highly heated carburetor in an amount sufficient to combine with the coke.

The theory upon which the process rests would appear to be substantially as follows:

When coke is left to accumulate in the carburetor, it is at such a high temperature at the end of the blasting operation that it is incandescent. In this state the coke, which comprises mainly carbon, is extremely active as a reducing agent. When the sulphur bearing oil is sprayed into the heated carburetor, it is vaporized and broken up into gases and vapors. There is an initial reaction whereby hydrogen sulphide is formed by the union of sulphur in the oil with heated hydrogen as represented by the equation

Due to the reducing effect of the incandescent coke, and the relatively weak union between the hydrogen and sulphur of hydrogen sulphide, part of the hydrogen is dissociated and the sulphur immediately unites

with the coke to form carbon disulphide in accordance with the following equation.

- 5 This latter gas is considerably more stable than hydrogen sulphide and is not further acted upon by the incandescent coke and passes through the apparatus to the gas holder. Hydrogen sulphide is also formed 10 in the generator and this also is reduced and the sulphur content changed to carbon disulphide. The amount of carbon disulphide formed from the generator gas appears to be 15 relatively small, however, in comparison with the amount which might be formed by the double reaction effected by the action of the incandescent coke on the oil.

It would be natural to expect that the constant presence of sulphur and free carbon 20 in this vaporized oil would necessarily result in the formation of carbon disulphide. Such, however, is not the fact when my process is used, at least the formation is not in prohibitive amounts.

- 25 When the carburetor is free or substantially free of coke, oil sprayed on the incandescent brick is vaporized as usual. Due to the comparative absence of coke the greater part of the sulphur content of the oil 30 is converted into hydrogen sulphide and very little into carbon disulphide. Hydrogen sulphide may be conveniently removed and any carbon disulphide formed exists, during this first run, in such small quantity 35 as to be commercially unobjectionable. During the steam run, which commonly lasts only about four minutes, coke will be deposited on the brick, but, due to the cooling effect of the oil, the temperature of the coke 40 layer will be so low that it will have no substantial reducing action on the oil sprayed in the carburetor during the remainder of the run. The resulting gas therefore will be substantially free from carbon disulphide.

- 45 If the coke is permitted to remain in the carburetor during the next run following the usual generator air blasting operation, it will have been heated to incandescence and will react upon the oil as above described 50 to form carbon disulphide.

It may be, with certain oils, that coke is but slowly accumulated in the carburetor and that it may be possible to make two or even more runs after each coke burning 55 operation before the average carbon disulphide content of the gas made during these runs become objectionably high. The necessary frequency of removal of the carbon can be determined readily by experiment.

- 60 I have found, however, that with oils such as the Mexican, it is desirable to burn out the coke previous to each run.

I have also found that by removing the 65 coke deposit in the manner above set forth, the amount of hydrogen sulphide in the

carbureted gas is also reduced. A considerable proportion of the sulphur content of the oil collects with the coke in the form of solid sulphur compounds on the checker work. When the coke deposit is permitted 70 to remain through succeeding runs the hydrogen of the generator gas, and probably also the hydrogen of the oil, reduces the solid sulphur compounds and forms hydrogen sulphide. When the coke deposit is burned 75 out at each operation the formation of hydrogen sulphide as above set forth is materially reduced.

This burning off operation should not be attempted while the generator gases are passing 80 through the carburetor as the air would unite with the combustible portion of the generator gas instead of with the coke on the checker brick.

Fig. 1 is a side elevation, partly in section, 85 of a gas making set adapted for the performance of the invention.

Fig. 2 is a perspective detail of the top courses of brick checker work in the carburetor illustrating the manner in which the 90 coke deposit is formed.

The water gas making set herein shown and adapted for the performance of the invention is of more or less common construction. The various elements of the set 95 include the water gas generator 10, the carburetor 11, and the superheater 12.

In the usual process for making carbureted water gas, steam is forced through a bed 100 of incandescent coal or coke in the generator, after said fuel bed has been blasted or heated by forcing air through it to burn with the fuel. Due to the reducing effect of the fuel a reaction occurs by which the steam combines with the carbon of the fuel 105 to form hydrogen and carbon monoxide in accordance with the equation.

and the product is termed water gas. If 110 the fuel contains sulphur compounds, and this is usually the case, a reaction also takes place between the steam and sulphur to form hydrogen sulphide as represented by the equation.

and the free oxygen combines with the fuel to form carbon monoxide or, possibly, carbon dioxide.

The resulting water gas, comprising hydrogen and carbon monoxide, with a small proportion of hydrogen sulphide, is deficient in heating value. It is consequently carbureted or has added to it gases by which 125 its heating value is enhanced. Said gases are added by passing the water gas about the highly heated checker work of the carburetor and superheater and spraying oil into the carburetor. Due to the high heat 130

the oil is converted into permanent gases which pass with the water gas to the gas holder.

Due to the cooling effect of the steam on the generator fuel bed, and the cooling effect of the water gas and oil on the carburetor and superheater, the usual gas making process is divided into a run or period of making carbureted water gas, of about four minutes, and a blast of about three minutes, during which steam and oil are turned off and air is forced through the generator fire to burn the fuel and raise its temperature. The blast gas contains a large proportion of carbon monoxide. It is passed through the carburetor and superheater and finally discharged through the stack into the atmosphere. In the carburetor the blast gas is mixed with air and burned to carbon dioxide and the resulting heat is utilized to raise the carburetor and superheater to a temperature at which the oil will be converted into fixed gases. When the blast is completed, the blast valves are closed and steam is again forced through the generator fire and oil sprayed into the carburetor for the next run. A gas making cycle, comprising a run and a blast, with time for manipulating the necessary valves, requires from five to seven minutes. The generator fire is cleaned about every eight to twelve hours.

Air is supplied to the ash pit of the coal or coke filled generator from the blower 13 under pressure through the pipe 13^a, and the flow of air may be controlled by the valve 13^b. A pipe 14 having a valve 15 therein extends from the top of the generator to the top of the carburetor and a second pipe 16 having a valve 17 therein extends from the ash pit of the generator and connects with the pipe 14 on the carburetor side of its valve 15 whereby the direction of making gas through the generator may be reversed when desired. Gas passed from the bottom of the carburetor through the pipe 15 into the superheater and from the top of the superheater either to the stack 19 or through the pipe 20 to the water seal 21 and thence to a gas holder not shown, depending upon whether the cover valve 19^a is open or closed. A waste heat boiler 30 may be inserted in the stack 19 to utilize the heat of blast products passing therethrough.

A carburetor blast pipe 22 extends from the blast pipe 13 into the upper part of the carburetor to supply air for blasting. Flow of air therethrough may be controlled by the valve 23.

I find it convenient to use this pipe 22 to supply the air to burn off the deposited coke from the checker brick in the carburetor though any other source of air could be used. I close the valve 13^b, and the valve 23 being open the air blast will pass into the carburetor and burn off the coke on the checker

brick. A short time will suffice for this operation.

Oil for enriching the generator gas is sprayed on to the top courses of brick of the checker work 24 in the carburetor through the pipe 25 which enters the carburetor through the top thereof; and the valve 26 controls the flow of oil.

The valve-controlled steam pipe branches 27 and 27^a serve to admit steam to either the top or bottom of the generator.

Oil having a high coke making and sulphur content injected into the carburetor contacts with the first course or two in the carburetor and is gasified. Carbon is separated from the oil and collects in the form of a layer of coke on the surface of the brick of the first course or two as indicated at A in Fig. 2. If the coke is left on the brick during successive runs the coke layer gradually will build up in thickness and work downward to lower courses of brick. The sulphur content of the oil sprayed on the incandescent coke layer is resolved into carbon disulphide and hydrogen sulphide, as above set forth. Removal of the coke deposit as above set forth results in a carbureted gas having a relatively low carbon disulphide content.

While carbon disulphide is the principal gaseous sulphur component, other than hydrogen sulphide, formed when oils having a high coke and sulphur content are employed, small proportions of other gaseous sulphur compounds are or may be formed which are herein included in the term carbon disulphide.

In case an oil is used which deposits coke in sufficient quantities to cause trouble even before the completion of one run the run may be shortened but I have never found it necessary to shorten the run.

The term "coke" as herein employed denotes the carbon which is separated from the oil and deposited in the carburetor; and the carbon may have associated with it other solids as sulphur compounds.

I claim:

1. An improvement in the method of making carbureted water gas from oil having a substantial carbon making and sulphur content which comprises, burning all the carbon from carburetor when or before the carbon disulphide content of the carbureted gas becomes objectionably high by substantially cutting off the water gas from the carburetor and driving a blast of air through the carburetor in the direction of water gas flow therein and between water gas making runs while the carburetor is highly heated, and discharging the resulting products of combustion produced by the burning from the carburetor.

2. An improvement in the method of making carbureted water gas from oil having

- a substantial carbon making and sulphur content which comprises, burning the carbon and sulphur deposit out of the carburetor previous to each water gas making run and to such an extent as to keep down the carbon disulphide content of the carbureted water gas, excluding the products of combustion resulting from the carbon burning from the generator and discharging the products of 10 combustion from the carburetor.
3. An improvement in the method of making carbureted water gas from oil having a substantial carbon depositing content which comprises, injecting the oil into the carburetor during each water gas making run and in removing all the carbon deposited in the carburetor before each succeeding water gas making run by a blast of air, excluding the gases formed by the car- 15
- bon removal from the generator and discharging them from the carburetor.
4. The process of making carbureted water gas in a gas making set comprising a generator and a carburetor, which consists in three steps, namely, an air blast run, a steam run including carbureting, and an independent run of free air through the carburetor.
5. The process of making carbureted water gas in a gas making set comprising a generator and a carburetor, which consists in three steps, namely, an air blast run, a steam run including carbureting, and an independent run of free air through the carburetor following the air blast run.

In testimony whereof, I have signed my name to this specification.

ALLEN E. SHIPPEE.
